UNITED STATES PATENT OFFICE.

ALFRED T. KRUSE, OF DEFIANCE, OHIO, ASSIGNOR, BY MESNE ASSIGNMENTS, TO THE AMERICAN STEEL PACKAGE COMPANY, OF DEFIANCE, OHIO, A CORPORATION OF OHIO.

BOX-FASTENER.

SPECIFICATION forming part of Letters Patent No. 786,299, dated April 4, 1905.

Application filed April 11, 1904. Serial No. 202,538.

To all whom it may concern:

Be it known that I, ALFRED T. KRUSE, a citizen of the United States, residing at Defiance, in the county of Defiance and State of Ohio, have invented certain new and useful Improvements in Box-Fasteners, of which the following is a specification.

My invention relates to improvements in box-fasteners, and is especially designed for use in connection with sheet-metal packing-cases used in the transportation and storage of bottled liquids, &c.

The primary object of this invention is to produce a generally improved device of this class which will be exceedingly simple in construction and efficient in use and which will be better suited to its intended purposes than any other device of the same class with which I am acquainted.

With these ends in view the invention consists in the novel construction, arrangement, and combination of parts hereinafter described, illustrated in the accompanying drawings, and particularly pointed out in the appended claims.

Referring to the drawings forming a part of this specification, Figure 1 is a top plan view of a portion of a sheet-metal packing-case provided with my improved box-fastener. Fig. 2 is a front view of the same. Fig. 3 is a sectional view taken through lines *a b* of Figs. 1 and 2. Fig. 4 is a detail view of one of the supporting-stops mounted in the front corners of the case and designed to take under the corners of the lid or cover and support the same in its closed position.

In the drawings, 1 designates a plate of sheet metal secured in any suitable manner to the front portion of the lid 2, intermediate the ends thereof and mounted in the present instance between two of the upwardly-extending ribs or flanges 3 of said lid or cover 2 and to the rear of the beading 4, formed about the edges thereof. 5 designates an upwardly and rearwardly extending flange or handle formed at the rear of said plate 1, and 6 designates an opening or recess formed in the front portion of said plate and registering with an opening

or recess formed in the front portion of the lid or cover 2.

7 designates a depression or pocket formed in the lid or cover 2 just beneath and slightly to the rear of the handle 5 and designed, together with the adjacent handle 5, to form a convenient handhold for opening and closing the lid.

8 designates a cross-bar formed within the opening or recess 6 and which is a part of the wire formed within the beading 4, formed about the edges of the lid or cover 2.

9 designates a spring latch or bar secured at its lower or base end to the front of the case by means of rivets, as shown, and bent at its upper or free end to form a hook 10, conforming to the contour of the cross-bar 8.

11 designates an opening formed in the front wall of the case opposite the spring-latch 9, and 12 designates a second opening formed in the spring-latch 9, which said opening 12, it will be seen, does not register with the opening 11, but is formed slightly out of alignment therewith, so that if a bar fitting said opening 11 is inserted therein it will engage the spring-latch 9, springing the same rearwardly and disengaging the hook 10 from the cross-bar 8, and the lid or cover 2 may be lifted by means of the handle 5.

When the lid or cover 2 is dropped or closed, the cross-bar 8 will come into engagement with the hook 10 of the spring latch or bar 9 and spring the same rearwardly until said cross-bar 8 has passed the hook 10, when the latter will snap into engagement therewith, thus automatically locking the lid or cover in its closed position. Should it be desired to seal the case, the wire of the seal is inserted and passed through the openings 11 and 12, formed in the case and spring-latch 9, respectively, and up through the opening or recess 6 and brought around and sealed, thus securely sealing the case and preventing the contents thereof from being tampered with in transportation or storage.

13 designates supporting-stops mounted in the front corners of the case and designed to take under the corners of the lid or cover

and support the same in its closed position and flush with the top or upper edges of the sides and ends of the case.

It will be seen that I provide a simple and efficient locking device in which there are no projecting parts protruding beyond the case proper to interfere with the proper and economical stacking of the cases or to be caught, broken, or disarranged, and one which may be quickly sealed when desired.

Various changes in the form, proportion, and the minor details of construction may be resorted to without departing from the principles or sacrificing any of the advantages of this invention.

Having thus described my invention, although without having attempted to set forth all the forms in which it may be made or all the modes of its use, I declare that what I claim, and desire to secure by Letters Patent, is—

1. A box-fastener for sheet-metal packing-cases, consisting of a plate secured to the lid or cover and provided at its rear with a handle, an opening or recess formed in the front portion of said plate and cover, a cross-bar mounted in said opening or recess, and a spring-latch secured to the front portion of the case and provided with a hook adapted 30 to take over and engage said cross-bar when the lid is closed.

2. In a box-fastener for sheet-metal packing-cases, the combination with a plate secured to the lid or cover and provided at its rear with a handle, an opening or recess formed in the front portion of said plate and cover, and a cross-bar mounted in said opening or recess; of a spring-latch secured to the front portion of the case, a hook formed at the top of said spring-latch and adapted to engage said cross-bar, and an opening formed in the front wall of the case, opposite said spring-latch, wherethrough the said spring-latch may be manipulated.

3. A box-fastener for sheet-metal packing-cases, consisting of a plate secured to the lid or cover, a handle formed at the rear of said plate, an opening or recess formed in the front portion of said plate and cover, a cross-bar secured in said opening or recess, a spring-latch secured to the front portion of the case and provided with an opening, a hook formed at the top of said spring-latch and adapted to engage said cross-bar, and an opening formed in the front wall of the case opposite said spring-latch, substantially as described.

In testimony whereof I have affixed my signature in presence of two witnesses.

ALFRED T. KRUSE.
